UNITED STATES PATENT OFFICE.

MILTON M. GOLDSTEIN, OF MINNEAPOLIS, MINNESOTA.

COMPOSITION FOR CLEANING ENAMELED SURFACES.

No Drawing.

Application filed April 28, 1920. Serial No. 377,151.

To all whom it may concern:

Be it known that I, MILTON M. GOLDSTEIN, a citizen of the United States, residing at Minneapolis, in the county of Hennepin and State of Minnesota, have invented certain new and useful Improvements in Compositions for Cleaning Enameled Surfaces, of which the following is a specification.

10 My invention relates to a composition for cleaning enameled surfaces. An object is to provide a composition which may be employed for cleaning enameled surfaces such as porcelain enameled surfaces without the injurious effects resulting from the use of abrasives or soaps.

The full objects and advantages of my invention will appear in connection with the detailed description thereof and the novel 20 composition of ingredients will be particularly pointed out in the claims.

In preparing my composition I mix the following ingredients,—an oily base of vegetable or mineral oil, preferably paraffin oil, 25 ten to thirty parts, benzol ten to thirty parts, and a light volatile oil such as gasoline or benzine fifty to seventy-five parts.

To these ingredients I preferably add nitro-benzol one-tenth of two parts. If desired a small amount of coloring matter, preferably oil soluble anilin green, may be added to give the mixture a more pleasing appearance. In use the surfaces to be cleaned are wiped with a moist cloth or rag on which has been placed a few drops of the mixture. 35 By the use of my composition above described I am able to quickly and thoroughly clean enameled surfaces without roughening such surfaces or impairing the luster thereof. 40

I claim:

1. A composition for cleaning enameled surfaces consisting of an oily base ten to thirty parts, benzol ten to thirty parts, and a light hydrocarbon oil fifty to seventy-five 45 parts.

2. A composition for cleaning enameled surfaces consisting of paraffin oil ten to thirty parts, benzol ten to thirty parts, and gasoline fifty to seventy-five parts. 50

In testimony whereof I hereunto affix my signature.

MILTON M. GOLDSTEIN.
